MIXING MACHINE AND METHOD

Claude B. Mills, Port Clinton, Ohio, assignor to
 United States Gypsum Company, Chicago, Ill.,
 a corporation of Illinois

Application April 25, 1934, Serial No. 722,258

6 Claims. (Cl. 83—73)

This invention relates to machines for mixing cementitious material with water and relates more specifically to mixing machines and methods in which air as an optional ingredient is mixed with cementitious materials and water.

In the manufacture of cementitious materials, such as gypsum wall boards and gypsum tiles and blocks, it is often desirable to make such products light in weight to improve the heat insulating value thereof. This low density is usually obtained by introducing air into the slurry in some way so that when the slurry sets to solid form, the resulting cast is filled with a multitude of small air cells. I have found that by the use of a special type of mixer, compressed air can be successfully introduced into a gypsum slurry. The mixer I have devised is of a type such that it will not readily clog up and become inoperative due to the building up of set gypsum on the inside of the mixer. I have found that additive fibrous materials, such as cornstalk fibers, may also be mixed with gypsum slurry and air through the use of my improved mixer and mixing method.

An object of this invention, therefore, is to provide an improved type of mixing machine which will operate continuously over long periods of time to mix quick setting cementitious materials, such as calcined gypsum.

Another object of the invention is to provide an improved mixing machine which is suitable for introducing compressed air in a gypsum slurry so as to produce a low density cast.

A further object of the invention is to provide an improved mixing method of incorporating fibrous material and compressed air into a gypsum slurry; also to improve mixing machines and methods in other respects hereinafter specified and claimed.

Reference is to be had to the accompanying drawings forming a part of this specification, in which

Fig. 1 is an elevation partly in section of my improved mixing machine,

Fig. 2 is a sectional elevation through the mixer taken on line 2—2 of Fig. 3,

Fig. 3 is a plan view partly in section of the mixer with cover removed,

Fig. 4 is a plan view of the mixer,

Fig. 5 is a bottom sectional view of the mixer disc,

Fig. 6 is a sectional elevation through the mixer disc taken on line 6—6 of Fig. 3, and

Fig. 7 is a sectional elevation through a modified form of mixer.

The mixing machine comprises an electric mo-

tor 10 with a vertical shaft 11 which is connected by a coupling 12 to a mixer shaft 13. Suitable bearings 14 and 15 serve to rotatably support the shaft 13, said bearings being supported on frame members 16a and 16 respectively. A collar 17 is secured near the upper end of shaft 13, said collar having an integral annular flange 18 on which a mixer disc 19 is supported. An annular housing 20 surrounds the disc 19, said housing having a bottom 21 and a cover 22 secured to said housing by means of bolts 23 and 23a respectively. A removable lid 24 in the form of a segment has its inner edge retained beneath a strip 25 which is secured to the cover 22. The outside edge of lid 24 is secured by hinged bolts 26 to brackets 27 on the housing 20. Handles 28 are secured to the lid 24 so that the lid 24 may be easily removed to permit cleaning the mixer and making repairs.

An inlet port 29 is provided in the cover 22 between the shaft 13 and the housing 20, a flange 30 being secured to said cover to connect to an inlet duct 31 which leads from a source of supply of cementitious material, such as powdered calcined gypsum. A water inlet pipe 32 is connected to the cover 22 somewhat nearer the center of shaft 13 than the duct 31 and arranged on one side of the duct 31 so that as the disc 19 is rotated in the direction of the arrow in Fig. 4, a film of water is deposited on the disc 19 to prevent the calcined gypsum from sticking to said disc. A main water supply pipe 33 is secured to the cover 22 on the side of the duct 31 opposite the pipe 32 so as to deliver an additional supply of water necessary to produce the correct consistency in the resulting slurry. The water inlet pipe 32 may be omitted if desired and satisfactory results will be produced. A series of compressed air inlet pipes 34, such as five in number, are preferably secured to the lid 24 around the outer edge thereof for introducing compressed air, or other density reducing fluid into the slurry and thus produce a low density cast. An air manifold not shown supplies all of the air inlet pipes 34 and an air pressure of 30-60 lbs./sq. in. is preferably maintained in this manifold while the mixer is in operation.

A plurality, such as four in number, of beater bars 35 are secured to the upper face of disc 19 preferably equally spaced about the periphery thereof. These beater bars 35 are preferably rectangular in cross section and are placed at an angle so that the broad face of each beater serves to strike the mixture of calcined gypsum and water, beat the mixture into a slurry, and throw the slurry outwardly against the housing 55

20 with great force. An outlet opening 36 is provided in the housing 20 to allow the slurry to flow out of the housing 20 onto a conveyor belt 37 traveling around a pulley 38. The belt 37 serves 5 to convey the slurry to a plasterboard machine or a block mold or to any other desired discharge point.

In order to prevent set gypsum from building up on the inside of the mixer, suitable scraping devices are provided to scrape all inside surfaces 10 of the mixer. Scraper bars 39 of elongated form are secured at intervals around the periphery of the bottom face of disc 19 by suitable means such as riveted screws 40, said bars 39 extending 15 at an acute angle to the disc radii so as to scrape the slurry from the upper surface of mixer bottom 21 and throw it outwardly against housing 20. A scraper bar 41 extends diametrically across the top of the mixer so as to scrape the 20 lower surface of cover 22 and lid 24. The ends of bar 41 are preferably secured to the tops of two of the beater bars 35 by means of screws 42. The center of the bar 41 is secured by screws 43 to a driving collar 44 and said collar is secured 25 by means of a key 45 to shaft 13. The collar 44 has a pair of diametrically opposite lugs 46 which engage in slots 47 in the disc 19 so as to cause the rotation of the disc 19 and bar 41. A nut 48 secures the bar 41 and collar 44 to the upper end 30 of shaft 13 and clamps the disc 19 onto the flange 18, said nut extending through a clearance opening 49 in the cover 22 and being covered by a cup 50. The mixer may be readily disassembled for 35 cleaning by removing cover 22, nut 48, collar 44 and disc 19. A suitable frame member 51 supports the bottom 21 of the mixer.

In the modified and preferred form of mixer construction shown in Fig. 7, a collar 53 is secured to the upper end of a mixer shaft 54 by 40 means of a nut 55 engaging a threaded section 56 on the upper end of said shaft 54, a washer 57 being interposed between said nut 55 and collar 53. An annular flange 58 is formed on the collar 53 and serves to support a mixer disc 59 which 45 seats around an annular shoulder 60 formed on the collar 53. A stud 61 has a lower annular flange 62 seating in an internal opening 63 formed in the disc 59. A clearance space 64 is formed in the bottom of stud 61 to clear the nut 55. 50 An outstanding annular flange 65 is formed on the stud 61 and bolts 66 serve to firmly secure the disc 59 between flanges 58 and 65. A diametrically arranged slot 67 formed in the top of stud 61 serves to receive a scraper bar 68 similar 55 to bar 41, a bolt 69 securing said bar 68 to said stud. A central opening 70 is formed in a cover 71 above the stud 61, and is closed by an annular plate 72. The other details of the modified form of mixer are substantially the same as in the 60 device shown in Figs. 1 to 6.

My improved mixer will mix calcined gypsum slurry continuously for long periods of time without a shut down. I prefer to mix vegetable fibers, such as cornstalk fibers with the calcined gypsum 65 entering the inlet port 29 and the mixer makes a very smooth slurry of highly desirable characteristics even with the use of fibers in the mix. The introduction of compressed air through pipes 34 can be readily controlled by suitable valves to

give any desired density in the resulting cast.

I would state in conclusion that while the illustrated example constitutes a practical embodiment of my invention, I do not wish to limit myself precisely to these details, since manifestly, 5 the same may be considerably varied without departing from the spirit of the invention as defined in the appended claims.

Having thus described my invention, I claim as new and desire to secure by Letters Patent:— 10

1. The method of producing a slurry of calcined gypsum containing entrained air, comprising mixing water and calcined gypsum while moving outwardly at a high speed from a center of rotation, and introducing air into said mixture during 15 said outward movement.

2. In a mixing machine, a disc rotatably mounted about a substantially vertical axis, a housing enclosing said disc and having an outlet port, means for introducing quick setting powdered cementitious material into said housing between the axis of rotation and the periphery of said disc, means for introducing water into said housing on opposite sides of said powdered material inlet, means for introducing compressed air into said housing adjacent the periphery of said disc, and beaters positioned adjacent the periphery of said disc for mixing the ingredients to deliver a slurry containing entrained air from said port.

3. In a mixing machine for gypsum slurries, 20 a disc rotatably mounted about a substantially vertical axis, a housing enclosing said disc and having an outlet port, beaters extending vertically adjacent the periphery of said disc, scrapers for cleaning the inside surfaces of said housing, and 25 means for introducing materials to be mixed into said housing on top of said disc.

4. The method of mixing materials, which comprises depositing a film of water onto the upper surface of a disc rotating at a high speed, depositing 40 a quick setting cementitious material onto said water film, adding additional water to said cementitious material, introducing air into said mixture, and beating the mixture to form a slurry containing entrained air.

5. In a mixing machine for gypsum slurries, a disc rotatably mounted about a substantially vertical axis, a housing enclosing said disc and having a cover and an outlet port, means for introducing calcined gypsum and water into said housing onto said disc, beaters on said disc to mix said water and calcined gypsum into a slurry to be delivered from said outlet port, and a scraper rotating with said disc and connected to some of 50 said beaters for scraping the inside of said housing cover.

6. In a mixing machine for gypsum slurries, a disc rotatably mounted about a substantially vertical axis, a housing enclosing said disc, said housing having a bottom spaced somewhat apart from the bottom of said disc, means for introducing calcined gypsum and water into said housing onto said disc, beaters on said disc to mix said water and calcined gypsum into a slurry to be delivered from an outlet port in said housing, and a scraper secured to the bottom of said disc for scraping set gypsum material from the upper 60 surface of said housing bottom.

CLAUDE B. MILLS.
